[57] CLAIM

The ornamental design for an anesthesia solution filter, as shown.

DESCRIPTION

FIG. 1 is a perspective view of an anesthesia solution filter, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a cross-sectional view taken along line 8—8 of FIG. 2;

FIG. 9 is a cross-sectional view taken along line 9—9 of FIG. 2;

FIG. 10 is a perspective view of a second embodiment of the anesthesia solution filter, showing my new design;

FIG. 11 is a front elevational view thereof;

FIG. 12 is a rear elevational view thereof;

FIG. 13 is a top plan view thereof;

FIG. 14 is a bottom plan view thereof;

FIG. 15 is a right side elevational view thereof;

FIG. 16 is a left side elevational view thereof;

FIG. 17 is a cross-sectional view taken along line 17—17 of FIG. 11; and,

FIG. 18 is a cross-sectional view taken along line 18—18 of FIG. 11.
